CLAIM

The ornamental design for a goggle, as shown and described.

DESCRIPTION

FIG. 1 is a bottom rear perspective view of a goggle showing the claimed design;

FIG. 2 is a top front perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top front perspective view thereof, in an environment in which it may be used; and,

FIG. 10 is a bottom rear perspective view thereof, in an environment in which it may be used.

The broken lines in the figures show portions of the goggle that form no part of the claimed design.
